INTERNAL COMBUSTION ENGINE

Filed Feb. 15, 1928

INVENTOR.

UNITED STATES PATENT OFFICE

JEAN A. H. BARKEIJ, OF WASHINGTON, DISTRICT OF COLUMBIA

INTERNAL-COMBUSTION ENGINE

Application filed February 15, 1928. Serial No. 254,543.

It is well known that internal combustion engines provided with a Ricardo head are subject to three serious drawbacks, 1, poor volumetric efficiency, 2, detonation, 3, piston 5 slap due to pressure on one side of the piston. The second drawback is however present more or less in any type.

The first drawback is due to the throat between cylinder and combustion chamber 10 and in an L-head construction this draw back is increased as the gases have to make a double curve to reach the cylinder space beyond the throat.

The real nature of detonation is still 15 shrouded in mystery. Several theories have been proposed, each of which might contain some of the truth. The only practical fact known with certainty is that detonation is more liable to occur in a great volume of gas 20 than in a small volume and for that reason the compression in small engines can be appreciably higher than in big engines.

It is the first object of this invention to improve the volumetric efficiency by placing the 25 inlet valve in the combustion space in the head and inverted, partially overlapping the cylinderbore. The double curve which the gas has to make in an L-head construction being eliminated, thereby increasing the volumetric efficiency of the engine, with an equal 30 valve area, appreciably. The second object is to retain the turbulence effect created by the throat and by the squeezing effect between the head and the piston, but to decrease the 35 tendency of detonation by splitting up the combustion space in two smaller spaces entirely separated from each other.

Fig. 1 shows a sectional view on the vertical section line S¹ in Fig. 2 of a cylinder, 40 and cylinderhead, having an exhaust passage and valve in the left combustion chamber, and an inlet valve and passage to the right combustion chamber.

Fig. 2 is a sectional view on the horizontal 45 section line S² of Fig. 1, showing the same parts.

Fig. 3 is a sectional view on the same horizontal section line S² of Fig. 1 of the same parts, when the valves are placed in the cylinder instead of in the head as in Fig. 1.

Fig. 4 is a horizontal section view on a section line S², lower than that shown as S² in Fig. 1, of a modified arrangement, where one exhaust valve is placed in the cylinderblock, and the inverted inlet valve in the head at 55 opposite sides of the piston, in order to form again two separate combustion chambers.

Fig. 5 is a vertical sectional view on two sectional lines, parallel to each other, like S¹ in Fig. 2, modification of Fig. 1, the valves 60 being placed at an angle in the head in two separate transverse planes in order to operate them with different cams on the same overhead camshaft.

Fig. 6 shows Fig. 5 on the horizontal section line S².

Fig. 7 shows the arrangement for the L-head motor on a horizontal sectional line S² similar to S² in Fig. 1, but lower through an L-head with two combustion chambers, lying over the cylinderbore 3^c and the valves 9 and 5, an inlet and an exhaust valve.

In all figures, 1 is the head, the undersurface 1^a of which cooperates with the upper surface 3^a of the piston 3 to create a turbulence in both chambers and to establish two separate combustion chambers with two separate sparkplugs. 2 is the cylinder, 4 is the exhaust valve, 4^a the exhaust passage, 5 the sparkplug for the exhaust combustion chamber to be discerned in a space 6 above the cylinderblock, and a space 7 above the piston. 8 is the inlet valve, 8^a the inlet passage, both of greater diameter than those for the exhaust, as usual; 9 the sparkplug for this inlet combustion chamber, which can again be divided in a space over the cylinder 10 and a space over the cylinderbore 11.

The cycle of operation for this arrangement is as follows: The exhaust gases are 90 pushed by the piston thru the throat 7^a past the exhaust valve 4 into the atmosphere. After the exhaust valve closes, the inlet gases pass the valve 8, the throat 11^a into the cylinderbore 3^c. From Fig. 1 can be seen, that 95 the fresh gases pass practically in a straight line from the inlet valve in the cylinder, which circumstance eliminates so much wire-drawing, that the volumetric efficiency is very much increased especially at high speeds. 100

The inlet valve closes, the piston comes up, the gases are pushed thru the two throats in the two combustion chambers during the entire compression period and cause thereby 5 already an appreciable turbulence. This turbulence is at the very last moment suddenly increased by the well known squeezing effect of the Ricardo head. The upper surface 3^a of the piston cooperates with the undersurface 10 face 1^a of the head to establish further two separate combustion chambers. This minimum clearance, however, has to figure on wear in the wristpin, connecting rod bearing, crankpin, crankshaft bearings, and journal 15 pins and it is not advisable to decrease this distance much more than to $\frac{1}{16}$ inch. The sparks pass simultaneously over the two points of the two plugs and the areas 7^a and 11^a being about the same, the explosion pressure 20 sure will not tip the piston in the cylinder and not cause that well known peculiar noise. The same balance is in this way established as in the balanced-pressure arrangement, shown in my application No. 238,587 of Dec. 25 8, 1927, for a single combustion chamber having more or less the form of a horse shoe. The cycle is completed.

Let us consider what exactly happens with the gas condition in the two chambers. After 30 the exhaust closes in the left chamber, the pressure will be here less than in the right chamber on account of the piston and head forming a barrier between the two, during the last part of the exhaust. With little gas, the 35 inlet gases will sweep the right combustion chamber clean, but not the left exhaust chamber and misfiring in this chamber is liable to happen. Increasing the amount of gas the ratio between the volume of burnt and fresh 40 gases will gradually approach an average, which will be the same for both chambers. The period of explosion with an extremely weak or rich mixture will be so long that the burning is still progressing when the piston 45 and head are at a distance considerably greater than the clearance space, but with a normal air-fuel ratio the burning takes virtually place in two separate chambers. The volume being small, the explosion period being smaller than for the total volume in a 50 single combustion space. A higher compression can therefore be used without the danger of detonation.

The throat 11^a is made wider than the 55 throat 7^a as it is, of course, easier to push the gases out than to introduce them in the cylinder under atmospheric pressure. Normally both throats are considered to have an area slightly in excess to the areas of the respective 60 inlet and exhaust valves. If a supercharger is used they may be respectively smaller in this sense that the ratios for both may be different. The inlet throat and inlet valve area is by the supercharging more affected than 65 the exhaust throat and exhaust valve area.

If a supercharger, a Roots blower or centrifugal type, is used the valves can be made smaller and also the throats. Without a blower the throat 11^a has to be larger than the inlet valve area. For the exhaust this is 70 not so necessary. The smaller the throats are, the greater are the squeezing surfaces of the head and piston and the more turbulence will be caused in the two chambers. The valves can be operated from a single cam-shaft in the crankcase by means of rocker 75 arms, as is well known.

The dotted lines 6^a and 10^a in Figs. 2 and 3 show that the combustion spaces can be considerably decreased if desired, which becomes 80 of prime importance already for bores of about 3 inches, as shown. The valves are shown with a minimum size for this bore.

Figs. 1, 2, 3, 5 show that the chamber with the inlet valve has a greater volume than that with the exhaust valve. This is not an absolute necessary feature of construction, but if the compression is carried up very high with special fuel (benzol, alcohol or mixture of gasoline and said fuels) the available compression space is very small and the size of the valves determine indirectly the size of the chamber.

The valves can be placed of course in the cylinder and a top view only of this arrangement is shown in Fig. 3 (compare Fig. 3 with Fig. 2) to illustrate clearly the considerable difference in the minimum volumes of the two chambers in the two constructions. In the L-head construction the chambers must be comparatively very shallow on account of their length. The overall width of the head and top part of the cylinder is excessive, compared with that of Fig. 2 and represents almost a difference of 50°. Considerable 100 weight, material and labor is saved and a compact engine with clean lines can be constructed on the basis of Fig. 1 and Fig. 2.

Fig. 4 shows that the exhaust valve 4 can be placed in the cylinderblock and the inverted inlet valve 8 in the head overlapping the cylinderbore as in Fig. 1. The latter valve can be operated from the same camshaft in the crankcase by a rockerarm. The two combustion chambers are again separated by the space of near-contact between piston and head 3^b as shown shaded.

Figs. 5 and 6 shows that the valves, if placed in the head can be very conveniently and directly operated by a single overhead-camshaft. The valves are placed in two different transverse planes to be operated by two different cams on the shaft. The combustion chambers can be made as compact as shown in Fig. 1. It is understood that the inverted inlet valve 8 of Fig. 4 can be equally placed at an angle as the inlet valve 8 of Fig. 5, and can be equally operated from a single camshaft.

Fig. 7 shows diagrammatically that the 130

same arrangement of two combustion chambers in the cylinderhead can be applied, mutatis mutandis, on an L-head construction, having both valves in the cylinder on the same side, instead of on opposite sides. This type is an extreme form or a continuation of the horseshoe type shown and discussed in my application No. 238,587, of Dec. 8, 1927 and that of Figs. 6-9 of my application No. 253,594, filed Febr. 11, 1928. The undersurface of the head ^{1a} is extended between the two valves, creating thereby two separate chambers, each chamber having one valve and one sparkplug. This arrangement however makes the unit of one cylinder and two valves rather broad and is favorable only for large 4 cylinder truck engines. A six cylinder would be rather long. Particularly is the attention drawn to the semicircle shape of the combustion chambers of Fig. 2. The flame propagating from the sparkplugs are supposed to spread at equal speed in all directions to the opposite walls, shown in a half circle. The particular phenomena experienced with this type of form of chamber is somehow connected with the socalled detonation of the fuel.

I claim:

1. An internal combustion engine of the fourcycle type, including cylinder, piston and cylinderhead formed with separate inlet and exhaust valve chambers, separated from each other by wide areas of small clearance between cylinderhead and piston, when the latter is at the end of its compression stroke, the inlet chamber affording most of the compression space, while the exhaust chamber is smaller than the inlet chamber, in combination with a spark plug in said inlet chamber, and one in said exhaust chamber.

2. An internal combustion engine of the fourcycle type, including cylinder, piston and cylinderhead formed with separate inlet and exhaust valve chambers separated from each other by wide areas of small clearance between the cylinderhead and the piston when the latter is at the end of its compression stroke, the inlet chamber affording most of the compression space, while the exhaust chamber is relatively small, in combination with separate spark plugs for each of said chambers.

3. An internal combustion engine of the fourcycle type, including cylinder, piston and cylinderhead formed with separate inlet and exhaust valve chambers, separated from each other by wide areas of small clearance between cylinderhead and piston, when the latter is at the end of its compression stroke, the inlet chamber overlapping the cylinderbore with an area greater than the overlapping of the exhaust chamber over said cylinder.

4. The combination of claim 1 in which said chambers overlap said cylinderbore,

thereby forming throats between said chambers and said cylinderbore, said valves in said chambers having respectively an area smaller than said respective throats.

5. The combination of claim 3 in which the area of the inlet valve is smaller than the area of the throat. ⁷⁰

6. The combination of claim 3 in which the effective inlet area of said inlet valve passage is smaller than the effective inlet area of said inlet throat between said cylinderbore and said inlet valve chamber. ⁷⁵

7. The combination of claim 3, in which said valves are located in the head overlapping partially said cylinderbore to increase the volumetric efficiency of said engine and to decrease the volume of each combustion chamber. ⁸⁰

8. The combination of claim 3, in which at least one of the combustion chambers has its valvular means located in the head, said means overlapping the cylinderbore to increase the volumetric efficiency. ⁸⁵

9. The combination of claim 3, in which at least one of said chambers, by preference the inlet chamber, has its valve overlapping the cylinderbore, said inlet valve having a greater capacity than said exhaust valve. ⁹⁰

10. The combination of claim 3, in which said inlet and said exhaust valves have different effective areas, and have different effective ratios between these areas; the respective restricted passages between these respective inlet and exhaust valve chambers having also different areas. ⁹⁵ ¹⁰⁰

11. The combination of claim 3, in which the respective valves of said chambers have different areas, the inlet valve being larger than the exhaust valve.

12. An internal combustion engine, having at least one combustion chamber in restricted communication with a cylinder, in which a piston reciprocates, valvular means in said chamber and spark ignition means in said chamber, said latter means arranged perpendicularly to the axis of said cylinder in a wall of said chamber, having substantially a straight surface; opposite said ignition means a wall, having substantially a semicircular form, all of said points in said latter wall being substantially at an equal distance from said spark ignition means. ¹⁰⁵ ¹¹⁰ ¹¹⁵

13. The combination of claim 12 in an engine, in which said piston and said cylinderhead form a separate inlet and exhaust valve chamber, separated from each other by wide areas of small clearance between cylinderhead and piston, the inlet chamber affording most of the compression space, while the exhaust chamber is smaller than the inlet chamber, in combination with a spark plug in said inlet chamber, and one in said exhaust chamber; each of said chambers having substantially the form and shape defined in said claim. ¹²⁰ ¹²⁵ ¹³⁰

14. The combination of claim 12 in which said piston and said cylinderhead form separate inlet and exhaust valve chambers, separated from each other by wide areas of small clearance between cylinderhead and piston, when the latter is at the end of the compression stroke; the inlet chamber overlapping the cylinderbore with an area greater than the overlapping of the exhaust chamber over said cylinder; each of said chambers having substantially the form and shape defined in said claim.

15. An internal combustion engine, having a cylinder, a piston reciprocating in said cylinder, a combustion chamber adjoining and communicating restrictedly with the end of said cylinder, said combustion chamber being entirely located in said cylinderhead when the piston is in the position of greatest compression, an inlet valve in said combustion chamber in inverted position overlapping the cylinderbore of said cylinder to facilitate the flow of gases from the atmosphere into said cylinder, said restricted communication formed at one side of said bore by the undersurface of said head and upper surface of said cylinder.

16. An internal combustion engine, having a cylinder, a piston reciprocating in said cylinder, at least one combustion chamber overlapping the cylinderbore of said cylinder, a throat between said combustion space and said cylinderbore, an inverted valve in said combustion chamber partially overlapping said cylinderbore facilitating thereby the flow of gases between said valve and said cylinderbore through said throat, said combustion chamber being entirely located beyond said throat in said cylinderhead, when said piston in the position of greatest compression, said throat formed at one side of said bore by said head and cylinder.

17. The combination of claim 16 in which said valve is an inlet valve, said valve overlapping said throat in order to facilitate the flow of gases from the atmosphere into said cylinder.

18. An internal combustion engine having a cylinder, a piston reciprocating in said cylinder, an exhaust valve and an inlet valve at least one of said valves in inverted position overlapping said cylinderbore above a throat between said cylinderbore and a combustion space partially overlapping said cylinderbore; said combustion space entirely located in a cylinderhead, closing the open end of said cylinder, when said piston is in the position of greatest compression; said combustion space containing said inverted valve above said throat.

19. An internal combustion engine, having a cylinder, a piston reciprocating in said cylinder, a cylinderhead arranged to afford a plurality of compression chambers, each chamber having at least one valve in in-

verted position above a restricted passage between said respective chamber and said cylinderbore, each of said valves overlapping said cylinderbore above said restricted passages, separate sparkplugs for said separate chambers.

20. An internal combustion engine, having a cylinder, at least two combustion chambers above said cylinder in a cylinderhead closing the open end of said cylinder; restricted passages between said cylinder and said combustion chambers, formed by said cylinder and said cylinderhead; at least one of said chambers having an inverted inlet valve in said head above one of said restricted passages and overlapping said cylinderbore to facilitate the flow of gas from the atmosphere into said cylinder; separate sparkplugs for each of said chambers.
